PHONOGRAPH OR SIMILAR ARTICLE

Arthur R. Bentsen, Liverpool, N.Y., assignor to General
Electric Company, a corporation of New York

Filed June 1, 1962, Ser. No. 70,384

Term of patent 14 years

(Cl. D56—4)

FIG.1

FIG.2

FIG.3

FIG.4

FIG.5

FIG.6

FIG. 1 is a perspective view of a phonograph showing my new design, with the record player in closed position;

FIG. 2 is a perspective view of the phonograph, with the record player in open or playing position;

FIG. 3 is a top plan view of FIG. 2;

FIG. 4 is a front elevational view;

FIG. 5 is a left side elevational view; and

FIG. 6 is a right side elevational view.

The rear view of the phonograph includes a rearmost wall of the cabinet which is substantially unornamented, and rear surfaces of the side doors that are substantially similar to the frontal surfaces thereof (viewing FIG. 1).

The dominant features of my design reside in the portions shown in full lines.

The design is characterized by an elongated cabinet body having a slimness of depth, a record player carrying door, a panel substantially matching said door disposed alongside of said door, a pair of speaker carrying doors hinged to opposite front ends of the cabinet body and which cover the entire front of said body when closed,

and a full width control panel above the record player carrying door and panel, all as shown.

I claim:

The ornamental design for a phonograph or similar article, substantially as shown and described.
